UNITED STATES PATENT OFFICE.

ROWLAND RUSHWORTH HIRST AND ARNOLD HIRST, OF HALIFAX, ENGLAND.

LAND ANCHOR.

Application filed February 10, 1927, Serial No. 167,302, and in Great Britain March 16, 1926.

Our invention relates to the means employed, in connection with tennis and like nets, to adjust the height of the centre part of the net, such means usually comprising a member, of adjustable length, clipped or otherwise secured at its upper end to the net cord or top band of the net and anchored at its lower end to a hook or the like carried by a socket driven into or held in the ground. It is to the anchorage for the lower end of the adjusting member that our invention has particular reference.

It is desirable that this anchorage shall be of such a character or construction that, when the adjusting member is removed, there shall be no projection above the surface of the ground which would interfere with the mowing or rolling of the surface of the court or playing area, and to this end it has been customary to provide an anchorage in the form of a vertically slideable hook having at its lower end an elongated eye engaged over a transverse pin or bar across the bore of the socket, so that when the adjusting member is removed the hook will drop down within the socket. This construction has the objection, however, that the open upper end of the socket is liable to become choked with soil or débris so that the sliding hook either will not fall properly or, if lowered, cannot be raised, and the object of the invention is to provide a form of anchorage which will obviate this.

A device according to the invention is characterized by the employment of two spaced pistons or plates mounted on a central shank or bolt and slideable in the bore of a socket. A set screw, inserted through a tapped opening in the wall of the socket, projects into the space between the pistons and limits the permissible extent of vertical movement of the shank or bolt. The upper end of the bolt has provision for attachment of the net adjusting tape or member, and the arrangement is such that when the device is in use the upper surface of the upper piston is level with the top of the socket, and when the adjusting member is removed the shank or bolt is supported with its upper end just below the level of the top of the socket.

The accompanying drawing will enable the invention to be clearly understood,

Fig. 1 showing the improved device, partly in section, with the net adjusting member applied, whilst

Fig. 2 is a view, similar to Fig. 1, showing the device with the net adjusting means removed.

Fig. 3 shows a slightly modified construction of the device.

Referring to the drawing, *a* represents a suitable socket, having a bore *a'* of, preferably, cylindrical section, and adapted to be sunk with its upper end level with the surface of the ground. A bolt or shank *b* has two pistons *c* and *d* mounted thereon at a suitable distance apart vertically, the upper end of the shank, above the piston *c*, having provision in the form of a hook *b'*, for the attachment of the net adjusting means which comprise in the instance shown an eye bolt *e* threaded into a sleeve *f* which, by means of a short chain *g*, is connected to a doubled tape *h*, the upper end of which passes over the upper edge of the net band in well known manner.

A set screw *i*, inserted through a tapped hole in the wall of the socket *a*, at an appropriate point below the top of the socket, projects into the space between the two pistons *c* and *d*.

The arrangement of the parts is such that when, as shown in Fig. 1 the net adjusting means are connected to the shank *b*, and tension is applied to the net, the screw *i* limits upward movement of the piston *d* and positions the upper surface of the piston *c* level with the top of the socket. When the adjusting member is removed, or the tension on the net is slackened, the screw *i* limits downward movement of the piston *c* and positions the top of the hook *b'* just below the level of the top of the socket, as shown in Fig. 2.

When the net is in use, therefore, the bore of the socket is closed, and no soil or débris can enter to choke it, so that when the adjusting member is removed the hook will not fail to drop below the level of the top of the socket. As the piston *c*, when in lowered position, is only a relatively short distance below the top of the socket, the amount of soil or débris which can enter the bore is only small and is insufficient to prevent the raising of the hook on re-attachment of the adjusting member, any débris which may have entered the bore being removed as the piston *c* rises under the pull of the adjusting member.

It will be apparent that, instead of employing two connected pistons as above described, the object may equally well be at-

tained as shown in Fig. 3 by employing a cylindrical block *j* slidable in the bore *a* of the socket, and having a longitudinal recess or keyway *j'* in its surface into which the end of the stop screw *i* may project.

Having thus described our invention, what we claim as new and desire to secure by Letters Patent is:—

An anchorage comprising a vertical socket to be embedded in the ground, a piston member slidable vertically in said socket and having a portion at its upper end to project

above the socket when said member is raised, and a removable projection carried by the socket and extending from the exterior into said socket, said member having a vertical recess receiving said projection for limiting the upward and downward movements of said member.

In testimony whereof we affix our signatures.

ROWLAND RUSHWORTH HIRST.
